CHARLES B. BARNITZ, OF BIRMINGHAM, ALABAMA

SIPHON VALVE FOR WATER-CLOSET TANKS

Application filed March 5, 1929. Serial No. 344,515.

This invention relates to valves for tanks, and more particularly to valve means for the flush tanks of water closets adapted to initiate siphonic action for discharging the contents of the tank into a water closet bowl.

The advantages of siphon discharge means for tanks of this character are well known, and numerous attempts have heretofore been made to provide mechanism in a siphon structure which will positively and unfailingly initiate siphonic discharge of the water in a tank and which will be free from the defects commonly inherent in such devices.

It is one object of my present invention to provide a novel type of plunger which shall be exceedingly simple and inexpensive in construction and positive in operation.

A serious difficulty experienced with the types of siphon heretofore in use is their failure to prevent ingress of air into the upper part of the shorter leg while the siphon is in action, since this upper portion must be apertured to receive a rod connecting the plunger and an external actuating lever or the like, and the fit of the rod in the aperture must be quite loose to prevent binding when the rod drops back to its original position. I have overcome this defect by a novel form of shorter leg and plunger construction, as will be presently explained.

A further object of my present invention is to provide a siphon whose longer leg is externally of a size to fit a standard gauge discharge pipe, but whose bore is constricted in part to assure initiation of siphonic action even when the volume of water lifted into the longer leg is relatively small, due to an insufficient pull on the plunger lifting means, wearing of the parts, or other causes.

The above and other objects will be apparent from the following description of the present preferred forms of my invention, taken in connection with the drawings, wherein

Fig. 1 is a part elevational view of my improved valve means, illustrating the application of the same in a water closet tank;

Fig. 2 is an end elevational view of the same;

Fig. 3 is a top plan view of the valve means, per se;

Fig. 4 is a horizontal sectional view, taken along the line 4—4 of Fig. 1;

Fig. 5 is a vertical, sectional view of the invention when mounted in the tank;

Fig. 6 is a detail, fragmentary sectional view of the invention, showing a modified form of plunger, the latter being illustrated in dotted lines;

Fig. 7 is a top plan view of the form of plunger shown in Fig. 6; and

Fig. 8 is a sectional view of the same.

Referring to the drawings, and first to Fig. 5, 1 designates a water closet flushing tank of well-known construction and of either the high or low type, in which the siphon valve means constructed in accordance with the present invention is mounted. The tank bottom has the threaded lower end of the longer leg 2 of the siphon passed therethrough and equipped with a flange 3 at the upper terminal of the threaded portion. An ordinary tank discharge pipe is provided, which is interiorly threaded to engage the projecting threaded portion of the longer leg 2. A flange 5 on the discharge pipe and a suitable gasket 6 are provided to afford a water-tight connection between the pipe elements and the tank.

The longer leg 2 is sleeved into a cylinder 7, which is integral with a dome 8, a connecting passageway 9 and a shorter leg 10, as appears to advantage in Fig. 5. It will be noted that the passageway 9 connects with the shorter leg 10 at one side thereof, so that the effective cross-sectional area of the leg 10 is much greater at its extreme upper end than at any other portion.

The shorter leg is open at its lower end and is supported a short distance, say about one inch, above the tank bottom by a foot 11. This shorter leg is preferably made circular in cross-section, and contains a complementary plunger.

The plunger 12 may be made of metal or other suitable material and has the periphery thereof turned upwardly and in contact with the inner periphery of the shorter leg 10 of the siphon. The plunger is provided with a

central enlargement projecting beyond both faces of the plunger, as indicated at 13, and is provided with a screw threaded bore. The enlargement on the upper face of the plunger is formed to provide a cup, more fully hereinafter described. The screw threaded bore of the socket is adapted to receive the lower screw threaded end of a plunger rod 16, the opposite end thereof extending through an opening 15 which is formed in the closed upper end of the shorter leg 10. The upper terminal of the rod is bent at right angles, as indicated at 17, to provide a stop for limiting downward movement of the plunger, in a manner well known in the art. Upon reference to Fig. 5 of the drawings, it will be apparent that the diameter of the opening 15 is relatively larger than the diameter of the rod 16, to permit the latter to slide freely therethrough.

In practice, the supply valve controlling means is adjusted to fill the tank with water to within a short distance, say one inch, of the upper end of the longer leg 2. With the water at this level, and with the parts in the position shown in Fig. 5, it is apparent that the shorter leg 10, the connecting passageway 9 and the lower part of the dome 8, will be filled with water, while the longer leg 2 and discharge pipe 4 will be empty. In this condition, a sudden lifting of the plunger will raise the column of water in the shorter leg and connecting passageway up into the dome 8, whence it will fall into the longer leg 2 and down the discharge pipe 4.

Siphonic action is thus initiated, which, continuing, raises plunger 12 by the convection of the current of water through the shorter leg until the socket 13 contacts with the margin of the aperture 15, as shown in dotted lines in Fig. 5. Further flow of water through the system is then allowed through the now unobstructed shorter leg and out of the opening in its side where the passageway 9 connects therewith. As long as this flow continues, the plunger is held against gravity in its uppermost position by the kinetic energy of the current. Upon cessation of the flow by reason of the water in the tank dropping to the level of the lower end of the shorter leg and uncovering the same to the atmosphere, the plunger drops to its initial position. Meanwhile, the tank supply valve (not shown) has opened to refill the tank and the rising water tends to seek its level in the shorter leg, which is now unobstructed by the lowered plunger.

As stated above, it has heretofore been proposed to provide valve means in the plunger to permit the rise of water through the same. According to the principle of my present invention, I accomplish this purpose by means of a small perforation 14 in the plunger, which provides a plunger that is simple and economical in the extreme and which of

course, can never fail to function through sticking of a valve flap or failure of any moving part. It is to be noted that the diameter of this perforation is sufficiently large to accomplish the function just explained, and at the same time is small enough to prevent passage therethrough of any great volume of water when the plunger is given its lifting stroke. I have found that a perforation with a diameter of about one-tenth that of the plunger gives excellent results.

It will be noted that two forms of plunger socket 15 are shown in the drawings, both provided with a half-round upper surface, but in one form this surface is concave, as at 18 in Figs. 4 and 5, while the other form, appearing in Figs. 6, 7 and 8, has a convex half-round upper surface 19. It will also be noted that two types of aperture 15 are illustrated; that used in combination with the concave surfaced socket being a plain cylindrical perforation; and that shown in combination with the convex topped socket being conical, flaring in its lower portion, as at 20 in Fig. 6, to provide a seat for the convex surface 19 of socket 15. I have found that either combination of socket surface and aperture is effectual in preventing ingress of air through the aperture 15 when the plunger 12 is in its uppermost position while siphonic action is taking place, but in practice I prefer the combination of concave socket surface 18 and plain cylindrical aperture 15, as shown in Fig. 5.

As hereinbefore explained, the perforation 14 in the plunger is made small enough to allow only a very small amount of water to pass therethrough when the plunger is moved upwardly to actuate the siphon. However, it is inevitable that some water will pass through this perforation, and if the pull on the actuating mechanism be unduly slow and gently, there would be danger that a longer leg of standard uniform inside diameter might not become sufficiently full of water to start the siphonic action. To obviate this contingency, I have provided a constricted portion 20 in the longer leg, as shown in Fig. 5. This arrangement sufficiently reduces the cross-sectional area of the longer leg at this point to enable even a relatively small volume of water gradually introduced to start siphonic action, while at the same time the external diameter of the threaded lower end of the leg 2 is large enough to engage a discharge pipe 4 of standard gauge. With such a form of longer leg it will be apparent that advantage may be taken of all the benefits of a plunger having an aperture 14, as above explained, without incurring any of the disadvantages which might otherwise be attendant upon this construction. It will be apparent, also, that while this novel type of longer leg is admirably adapted for use in connection with the novel plunger which

forms one element of my invention, it may also be advantageously used in any siphon where the volume of water lifted in the shorter leg may at times be less than that necessary to initiate siphonic action through a longer leg of uniform internal diameter.

An afterfill spud, kept normally capped, may be provided in the top of the dome 8, at 21, as is sometimes required by city plumbing regulations.

It is to be understood that I have shown and described my invention in only one form of embodiment. Modifications will readily suggest themselves to persons skilled in the art to which this invention relates, but all such modifications are to be considered with the spirit of my invention and the scope and purview of the appended claim.

What is claimed is:

20 In a siphonic action water closet tank, siphon creating means including a long and a short leg, a passageway placing the tops of the legs in communication and having a relatively large perforation therein in alignment 25 with the axis of the short leg, a plunger mounted in the short leg, a rod connected to the plunger having a diameter substantially less than that of the perforation and passing through the perforation to provide means for 30 reciprocating the plunger, in combination with an enlargement on the rod to make fluid tight engagement with the passageway adjacent the perforation, the inner surface of the long leg being provided at a point intermediate its ends with an inwardly and upwardly projecting flange to abruptly constrict the bore of said leg, said bore being narrowest at said flange and gradually widening from the flange to the outlet of said leg.

CHARLES B. BARNITZ.
